ROBERT M. HOLLAND, OF PHILADELPHIA, PENNSYLVANIA.

Letters Patent No. 66,711, dated July 16, 1867.

IMPROVED RAILROAD CHAIR AND SLEEPER

The Schedule referred to in these Letters Patent and making part of the same.

TO ALL WHOM IT MAY CONCERN

Be it known that I, ROBERT M. HOLLAND, of Philadelphia, Pennsylvania, have invented a Combined Railway Chair and Sleeper; and I do hereby declare the following to be a full, clear, and exact description of the same.

My invention consists of a cast-iron girder or beam, constructed as and combined with the appliances fully described hereafter, so that it may serve as a substantial sleeper, as well as chairs, to which the rails may be readily secured, and from which they may be as readily detached.

In order to enable others skilled in the art to make and apply my invention, I will now proceed to describe its construction and operation, reference being had to the accompanying drawing, which forms a part of this specification, and in which—

Figure 1 is a side view of my combined chair and railway sleeper.

Figure 2 is a plan view; and

Figure 3, a section on the line 1-2, fig. 1.

A is a cast-iron beam or girder, which is open at the bottom, closed at the ends, and has on each side an inclination terminating in a central rib, *a*, as shown in fig. 3. At each side of the girder A, near the lower edge of the same, is a flange, *c*, which is strengthened by fillets *e e*, and in the rib *a*, near each end of the girder, is a recess, *x*, one end of which is formed to receive the side of a rail, *X*, which rests at right angles to the girder on a plate, *i*, secured at the bottom of the recess *x*, in which fits a metal block, *B*; and on one end of the latter are projections *m* and *n*, the former fitting against the rail *X*, and the latter underlapping the bottom flange of the rail and plate *i*, and embracing the rib *a* of the girder. To each side of a projection, at the rear end of the block *B*, is jointed one end of a link, *C*, and through the rib *a* of the girder, and through a slot in the inner end of each link *C*, passes a pin, *s*. In each link *C* is a slot, *t*, which when the link is in the position shown in fig. 2, corresponds with a slot in the rib *a*, and through these slots passes a key, *u*, the central portion of which is equal in width to the height of the slots, while the ends are of such a width that when the plate is turned on its edge, as shown on the right in fig. 1, it cannot be withdrawn from its position. As long as the block *B* is depressed in the recess *x* and bears against the side of the rail, the latter is effectually prevented from rising, while the upward movement of the block, as well as any lateral movement of the same, is prevented by the projections *n n* and the plate *i*. Should it be necessary to remove the rail, the key *u* is turned on its side and withdrawn from the slots *t t*, the outer ends of the links *C* are raised until the blocks *B* are drawn back to the position shown on the right of fig. 1, when the rail may be detached from the sleeper. The material of which the sleeper is formed renders it strong and durable; and owing to its peculiar shape, such an extended bearing surface is obtained that the sleeper, when embedded to but a slight extent in the earth, cannot be displaced from its position; at the same time it forms, in combination with the appliances described, a most efficient chair. Although the plate or key *u* affords additional security, it may be dispensed with.

Without confining myself to the precise construction and arrangement of parts herein described, I claim as my invention, and desire to secure by Letters Patent—

1. A sleeper consisting of a cast-iron beam or girder, to which are connected the above-described devices or their equivalents, for securing the rails to the top of the girder and permitting their withdrawal therefrom.

2. The girder A, with its recesses *x*, in combination with the blocks B and links C, the whole being constructed and arranged substantially as described, for the purpose specified.

In testimony whereof I have signed my name to this specification in the presence of two subscribing witnesses.

ROBERT M. HOLLAND
